(57) **CLAIM**

The ornamental design for a cop-box, as shown and described.

DESCRIPTION

FIG. 1 is a front perspective view of a cop-box, showing my new design;

FIG. 2 is a rear perspective view thereof;

FIG. 3 is a front elevation view thereof;

FIG. 4 is a rear elevation view thereof;

FIG. 5 is a left-side elevation view thereof, the right-side elevation view being a mirror image thereof; and,

FIG. 6 is a top plan view thereof, the bottom plan view being a mirror image thereof.

The broken lines shown in the drawings depict portions of the cop-box that form no part of the claimed design.

In FIGS. 2 and 4, the use of stippling indicates a contrasting appearance with the adjacent line-shaded portions of the cop-box.
